ICE SKATE

Charles E. Jones, Chicago, and William G. Crowle, Berwyn, Ill., assignors to Daniel D. Kipnis and Emanuel Schwartz, Chicago, Ill.

Application March 7, 1957, Serial No. 45,139

Term of patent 14 years

(Cl. D34—14)

Fig. 1.

Fig. 2.

*Fig. 3.**Fig. 5.**Fig. 4.*

Fig. 1 is a top plan view of an ice skate, showing our new design;

Fig. 2 is a side elevational view, the opposite side having substantially the same appearance;

Fig. 3 is a bottom plan view thereof;

Fig. 4 is a rear elevational view; and

Fig. 5 is a front elevational view.

We claim:

The ornamental design for an ice skate, substantially as shown and described.
